UNITED STATES PATENT OFFICE.

MANETHO C. JACKSON, OF MADISON, WISCONSIN.

RIVETING MACHINERY.

1,113,900.

Specification of Letters Patent. Patented Oct. 13, 1914.

Application filed March 13, 1913. Serial No. 753,970.

To all whom it may concern:

Be it known that I, MANETHO C. JACKSON, a citizen of the United States, residing at Madison, in the county of Dane and State 5 of Wisconsin, have invented a certain new and useful Improvement in Riveting Machinery, of which the following is a full, clear, concise, and exact description, reference being had to the accompanying drawings, forming a part of this specification.

My invention relates to riveting machinery and has for its object an improved mechanism whereby riveting can be done in a very effective and simple manner.

My invention provides mechanism wherein in a motor and the riveting mechanism *per se* is movable with respect to a table upon which the parts to be riveted are placed.

My invention provides a rivet set which 20 is adapted to be rotated by a motor at such times when it is raised from the rivet upon which it has operated, and when the rivet set is in actual contact with the rivet a slip friction is provided so as not to interfere 25 with the rotation of the motor. By the use of this slip friction the rivet set may receive a rapid succession of blows without injury to the motor or the riveter parts. The rivet set is of such a construction that it engages only a part of the rivet at one time, so that there is not a great deal of power 30 required to perform the riveting.

My invention also contemplates portable riveting mechanism thus dispensing with the 35 supporting means.

My invention will be clearly understood by referring to the accompanying drawings, in which:

Figure 1 is a front elevational view of the 40 mechanism embodying my invention. Fig. 2 is a view wherein the parts shown in cross-section are taken on the line 2—2 of Fig. 1. Fig. 3 is a sectional view taken on line 3—3 of Fig. 2. Fig. 4 is a sectional view taken 45 on line 4—4 of Fig. 2. Fig. 5 is an enlarged view of the spring mechanism which is associated with the rivet set. Fig. 6 is a fragmentary view showing the engagement of the operating member with the plunger 50 which is used to strike the rivet set. Fig. 7 is a modified arrangement of the rotating member showing a modified arrangement of the upper bearing members. Fig. 8 is a view showing the rivet set in section and 55 also showing how this rivet set is advanced after it has been made to strike the rivet.

Fig. 9 is a sectional view of a modified arrangement for the engagement of the rivet set with its associated sleeve.

Referring to Figs. 1 and 2, there is shown a base 10, which is suitably supported, and extending upwardly from this base at each side thereof are two ribs 11—11, which at their upper ends support two guides 12—12. These guides have operating engagement 60 with flat surfaces 13—13, upon the frame 14, which is adapted to be moved up and down. This frame 14 has mounted at the top thereof, a motor frame 15—15. At the lower end of this frame there is secured a cup member 16. The frame 14 has at its rear end a recess 17, which is engaged by a ball member 18, which may be secured to the levers 19, pivoted at 20 to the ribs 11—11. One of the levers 19 has pivoted 65 thereto, a rod 21, which leads downward and is pivoted at its lower end to a foot lever 22, which is suitably pivoted to a support, as shown. The other lever has secured thereto a spring 23, which has one end secured to a hook member 24, which is suitably mounted upon a cross piece 25, bridging the distance between the web members. The purpose of this spring is to maintain the motor frame 15 and the frames 14 and 16 70 in their normally raised position, that is to say, this spring maintains these parts in the dotted position, as shown. At the upper ends of the ribs 11—11, a bridge member 26, is shown, which supports the upper end of a vertical spindle 27, which passes through a lug 28, formed in another bridge piece 29. The sleeves 30 and 31, which are suitably secured to this vertical spindle, prevent longitudinal movement 75 thereof. The spindle has at its uppermost end, a suitable handle, so that it may be rotated when desired. The lower end of this spindle is threaded into a lug 32, which is a part of a table 33, which is adapted to be moved up and down, as occasion requires. This table is provided with engaging surfaces 34—34, which engage vertical operating surfaces 35, on the ribs 11—11. Opposite from these operating surfaces are operating surfaces 36—36, which are slightly inclined, as shown, and which are adapted 80 to be engaged by a block 37, which has a bolt 38, passing therethrough, and also through the table 33. This bolt when tightened by means of the nut at one end thereof, serves to hold the block and table firmly.

against their associated engaging surfaces. The table is provided at its upper end with a member 39, for engagement with the head of the rivet.

It might be well to explain now the mechanism for operating the rivet set, and in order to do this effectively, and in the most simple manner, I have shown a motor shaft 40, which extends downward and is splined in a neck portion 41, of the rotating member 42. This rotating member is provided with a shoe or lug 43, which may be either integral with said member or may consist of a separate piece which may be fixedly secured to said rotating member. This rotating member has extending downward a bearing portion 44, which is supported in a sleeve 45, which is held in the frame 14, as shown. The bearing portion 44, has an opening 46, into which projects a vertical shaft 47, a connection being made by passing a pin 48 extending from the portion 44, and into an elongated slot in the shaft 47. This arrangement it will be seen, provides for relative movement between the member 42 and the shaft 47. The shaft 47 has bearing engagement with the frame 14, and at the lower end it has bearing engagement with a sleeve 49, which is suitably supported in the frame 16. The shaft 47, has provided at its lower end, a pinion 50, which is clearly shown in Figs. 2 and 3, and which engages with a gear 51, which has extending downward therefrom a sleeve 52, this sleeve having bearing engagement with the frame 16, as shown. Extending upwardly from the gear is a cup portion 53, which serves to support the lower portion of a sleeve or thimble 54, this thimble having quite a long engagement with the cup portion 53. The sleeve 54 is arranged so that it engages at its upper portion with a shoulder 55, this shoulder preventing movement in an upward direction of this thimble. The thimble is provided with an opening 56, which admits a plunger 57, which is arranged to reciprocate in this opening in a manner which will be described hereafter. The plunger 57 has an enlarged portion 58 thereon, which engages the opening 56 and is arranged to be held in its up position by means of a short spring 59, which bears against a floating sleeve member 60, this member having a neck portion which is adapted to engage the lower portion of the plunger 57. One purpose of this member 60 is that it serves to limit the upward movement of the rivet set 62 when said member engages the sleeve 54 forming a stop therefor. Another purpose of this member 60 is that it controls the position of the plunger 57 through the spring 59. As shown in the drawings, the plunger is normally in a position out of the path of the shoe or lug 43 owing to the shortness of the spring 59. The upper portion of the plunger

57 is splined to a member 61, which is mounted in the frame 14, in order to prevent said plunger from turning.

The sleeve 52 has an opening into which the upper portion of the shank of the rivet set 62 is adapted to engage. This rivet set is provided with a diminished portion 63, around which engage a pair of springs 64 and 65, these springs serving to maintain the rivet set in a position such that the rivet set will have more or less loose connection upon the sleeve portion 52, and also, as will be presently described, the connection is such that after a blow has been struck on the rivet set by means of the plunger 57, the springs 64 and 65 serve to maintain sufficient friction between the rivet set and the portion 52 so that the rivet set is rotated a slight amount and can rebound or reciprocate after each striking operation. Rotation is produced by the engagement of the pinion 50 and the gear 51. The springs 64 and 65, as shown in Figs. 1, 2 and 5, have each an upper loop 66, and the lower loop 67, which are connected by a portion 68, as shown. The upper loop of each spring engages in a recess which is suitably formed in the sleeve portion 52 and has a frictional engagement therewith. The loops 67 have frictional engagement with the portion 63, so that when the rivet set is brought against the rivet and during such engagement, this rivet set will not be turned because the friction is only sufficient to turn the rivet set after each striking operation, or during the disengaged position.

In one form employed in my invention the rotating member 42 has engaging therewith a resilient member 69, which also engages a plate 70, which has bearing engagement with roller bearings 71, which in turn engage with a suitable plate 72. Suitable ball bearings are also provided around the uppermost portion of the neck 41 of the rotating member. This arrangement provides means whereby very little friction ensues during the operation of the rotating member 42, and also provides a connection such that this rotating member is raised slightly as it strikes the end of the plunger 57. In the arrangement shown in Fig. 7, the rotating member 42^a, is provided with a suitable race-way which engages suitable ball bearings which in turn engage a race-way engaging the motor frame 15. The member 42^a has a neck portion 41^a between which and the motor frame 15, there are a plurality of thrust washers 74. These washers are arranged so that they receive the thrust when the rotating member 42^a strikes the plunger 57. In this modification there is no relative movement between the motor frame and the rotating member 42^a, so that each blow struck on the plunger will be sharp and decisive and not yielding, as is the case with the ar-

angement shown in Fig. 2. In this connection, the vertical shaft 47 may have a fixed connection with respect to the rotating member 42.

5 As shown in Fig. 9, the rivet set 62, has a shank 75, which is splined to the sleeve portion 52, by means of a key 76, so that there will be a continuous rotation of the rivet set, as distinguished from the other arrangement wherein there is only a rotation when the rivet set is removed from the work upon which it operates.

10 The operation of the machine is as follows: A piece of work such as a pair of plates are placed upon the table 33, which may be raised to the required height, after which the nut on the bolt 38 may be tightened so as to maintain this table in a positive and fixed position. It is to be understood of course that normally the frames 14, 15 and 16 are in a raised position owing to the tension of the spring 23, which maintains such parts in a normal position, and when it is desired to perform the riveting, the 15 foot lever 22 is pressed downward, thus causing a downward movement of the above-mentioned frames against the tension of the spring 23. When the rivet set has been brought into contact with the rivet, the rivet set is forced up into engagement with the sleeve 60, and also into striking distance with the end of the plunger 57. This movement it will be noted presses the enlarged portion 58 of the plunger into firm engagement with the thimble or sleeve 54, owing to the increased tension placed in the spring 59. After the rivet set has been brought into firm engagement with the rivet by pressing the foot lever, or by hand pressure 20 when the portable type is used, the motor is set in operation and the rotating member 42 is caused to rotate in order that the shoe or projection 43 may strike the end of the plunger 57. This plunger, as shown in Fig. 6, 25 has an inclined surface against which the shoe strikes. When this action takes place, the plunger is forced downward compressing spring 59 and striking the rivet set, the rivet set is also forced downward in order 30 to do the required work upon the rivet. In other words, it upsets the metal and forms a head on the rivet in order to secure the plates or parts together. After each striking operation the spring 59 forces the plunger into its uppermost position against the neck portion provided in the thimble or sleeve 54. There will not, however, be any rotation of this plunger inasmuch as it is splined at its upper portion to the sleeve 61, 35 which is firmly held in position in the frame 14. Fig. 8 illustrates the end of the rivet set, this end being shown in cross-section and in dotted lines; that is to say, the full lines represent one position of the rivet set, and the dotted lines represent the position

40 to which this rivet set has been advanced after the rivet set has been struck by the plunger. It will thus be seen that the rivet set engages but a very small portion of the rivet at one time so that very little power is required to upset the metal. The rivet set is turned after each striking operation, and it makes a complete revolution in order to operate against all portions of the rivet. It will be understood, of course, that the engagement between the rivet and the rivet set 45 may be maintained until a head has been formed on the rivet. With the spring connection between the rivet set and the sleeve portion 52, provision is made so as to prevent the increase of the normal load on the motor, that is, no turning action is carried on when the rivet set engages with the rivet, but only during such times when there is a rebound or when the rivet set is raised from 50 the rivet.

55 The provision of the floating thimble 60 is a very important feature in that it controls the position of the plunger by means of the spring in addition to serving the purpose of preventing the rivet set from being forced into a rigid engagement with the plunger. In other words, the rivet set is limited in its movement in an upward direction by the engagement of the floating sleeve 56 with the sleeve 54 forming a stop. This 55 prevents the overloading of the motor.

60 It is to be understood that my invention is designed to be employed with equal facility as a stationary as well as a portable device. 100 When it is used as a portable means a suitable handle can be secured to the motor frame if desired in order to aid in lifting and holding the mechanism.

65 What I claim is:

1. A mechanism of the class described comprising a source of power, a reciprocating element driven from said source, a tool arranged to be engaged and operated by said reciprocating element, mechanism for transmitting power from said source to rotate said tool, and a friction clutch arranged to permit said power-transmitting mechanism to move independently of said tool when said tool is being acted upon by said reciprocating element.

110 2. A mechanism of the class described, comprising a source of power, a hammer operated from said source, a tool arranged to be engaged and operated by said hammer, mechanism normally adapted to turn said tool, and a friction clutch arranged to permit said mechanism to move independently of said tool when said tool is being acted upon by said reciprocating element.

120 3. In combination, a source of power, a reciprocating element driven from said source, a tool arranged to be engaged and operated by said reciprocating element, and mechanism for normally continuously rotat-

105

110

115

120

125

130

ing said tool arranged to permit said tool to remain nonrotating while the latter is being acted upon by said reciprocating element.

5 4. In combination, a source of power, a hammer operated from said source, a tool arranged to be engaged and operated by said hammer, and mechanism for normally continuously rotating said tool arranged to permit said tool to remain nonrotating while the latter is being acted upon by said hammer.

10 5. In combination, a source of power, a hammer operated from said source, a tool arranged to be engaged and operated by said hammer, and power-transmitting mechanism interposed between said source and said tool for rotating said tool, said power-transmitting mechanism arranged to permit said tool to remain nonrotating while the latter is being acted upon by said hammer.

15 6. In combination, a source of power, a hammer operated from said source, a tool arranged to be engaged and operated by said hammer, a collar encircling said tool, mechanism for continuously rotating said collar from said source of power, and means affording a yielding frictional connection between said tool and said collar arranged to permit said collar to momentarily slip relatively to the tool while the latter is being acted upon by said hammer.

20 7. Mechanism of the class described, comprising a source of power, a hammer operated from said source, a riveting tool arranged to be engaged and operated by said hammer, a collar encircling said tool, mechanism for continuously rotating said collar from said source of power, and means affording a yielding frictional connection between said tool and collar arranged to permit said collar to momentarily slip relatively to the tool while the latter is being 25 acted upon by said hammer.

25 8. In riveting machinery, the combination of a motor, a riveting tool driven by said motor, a plunger, means for reciprocating said plunger, a stop, a member engaging said plunger interposed between said plunger and said riveting tool, said member limited in its forward movement by said stop, and a spring engaging said

member to maintain it in its down position, said member being adapted to prevent the riveting tool from being forced into rigid engagement with said plunger.

9. In riveting machinery, the combination of a motor, a riveting member driven by said motor, a plunger, means for reciprocating said plunger, and a floating thimble engaging said plunger for preventing the riveting member from being forced into rigid engagement with said plunger.

10. In riveting machinery, the combination of a motor, a riveting member driven by said motor, a plunger, means for reciprocating said plunger, a stop, a floating thimble engaging said plunger and limited in its forward movement by said stop, a spring engaging said thimble to maintain it in its down position, said floating thimble being adapted to prevent the riveting member from being forced into a rigid engagement with said plunger.

75 11. In a riveting device, the combination of a rivet set, a reciprocating plunger for imparting blows to said rivet set, a spring for holding the plunger at one end of this movement, a rotating member for imparting blows to the plunger, said plunger being normally held out of the path of said rotating member, the rivet set being movable into the path of the plunger to a desired extent, a stop, a thimble engaging said plunger, and co-operating with said stop so as to prevent the rivet set from being forced into a rigid engagement with said plunger.

80 12. In riveting machinery, the combination of a motor, a riveting member driven by said motor, a plunger, mechanism driven by the motor for reciprocating said plunger comprising a rotating member, said plunger being normally disposed out of the path of said rotating member, means for raising said plunger into the path of said rotating member when the riveting member is pressed upwardly, and a stop for limiting the movement of said riveting member.

85 90 In witness whereof, I hereunto subscribe my name this 1 day of March, A. D. 1913.

MANETHO C. JACKSON.
